UNITED STATES PATENT OFFICE.

GEORGE CLAUSING, OF PORTSMOUTH, OHIO, ASSIGNOR TO THE VULCAN LAST COMPANY, OF PORTSMOUTH, OHIO, A CORPORATION OF OHIO.

LAST.

Application filed February 4, 1924. Serial No. 690,434.

To all whom it may concern:

Be it known that I, GEORGE CLAUSING, a citizen of the United States, residing at Portsmouth, in the county of Scioto and State of Ohio, have invented certain new and useful Improvements in Lasts, of which the following is a specification, reference being had therein to the accompanying drawing.

10 My invention relates to lasts, and in particular to collapsible lasts.

The object of my invention is to provide a collapsible last which may be firmly held in extended and collapsed position and which will have a toe portion collapsed or extended simultaneously.

It is a further object of my invention to provide last parts of resilient material.

It is my object to provide a last so constructed of such material that the material is compressed or yields when the last parts are moved from expanded to collapsed position and vice-versa, because the distance between the centers of attachment of the link when the last is in collapsed position is less than the length of the resilient material of the last parts between such centers when the last is moved to extended position, so that the resilient material is compressed when the line joining such points of attachment of the link passes over dead center of the last hinge. This flexibility or yielding nature of the material permits of this movement.

35 It is my object to provide also a link attachment for collapsing the instep portion of the toe part when the remainder of the last is collapsed, this link being located within the limited area available in the same slot which houses the other link parts, without modifying or disturbing such link parts or their operation. It is my object to provide this link, so that it will not be exposed where it can be tampered with and so that it will present a strong and durable construction which will positively collapse the instep portion of the toe part, and also to support it firmly when in extended or unbroken position.

45 50 It is a further object of my invention to provide link mechanism of yielding character in combination with the collapsing mechanism for the toe or instep portion.

It is a further object of my invention in

order to ensure the proper compressing and yielding of the last material and also the link mechanism, that the holes when bored in the last and before assembling, or the attaching of the hinge mechanism, are of a greater distance apart than the holes in the hinge link. This is necessary to allow for the thickness of the saw scarf plus an additional amount to ensure the heel part and the toe part having sufficient draw or tension so that when the last is assembled in the full collapsed position or a full extended position, it will ensure a snapping movement as it passes over the dead center in being moved from a collapsed to an extended position and vice-versa, as it will be apparent that the greatest stress or draw will come on the dead center when passing from a collapsed to an extended position when bored and assembled in this manner.

With these objects in view, the drawings will be more clearly understood.

The use of a last of relatively rigid material and spring pins is also an object of my invention.

Referring to the drawings:

Figure 1 is a section showing the last and toe portion in expanded position.

Figure 2 is a similar view showing the parts in collapsed position.

Figure 3 is a section on the line 3—3 of Figure 1, showing in particular the arrangement of the links and the supporting spring pins.

Figure 4 is a perspective of a typical link installation between the last parts.

Figure 5 is a side elevation of a modified form of link.

Figure 6 is a view on the line 6—6 of Figure 1, looking forwardly in the direction of the arrow and partially in section.

In general, it will be understood that the center of the hinge passes by a line drawn between the centers of the spring pins which support the link joining the last parts, when the last parts are moved from collapsed to extended position, or vice-versa. The compressible nature of the wood permits it to be compressed when the parts pass over the dead center, as the distance between the holes in the ends of the link is less than the distance between the hole in the material of the last when the parts move over the dead center.

In this construction there is also provided pins which are adapted to be sprung or deflected when this dead center is passed, so that either the wood may be compressed, or 5 the pins may be deflected, or both.

It will also be noticed that it is desirable to draw the toe portion into its smallest compass by some positive means which will not project into the V-shaped openings between 10 the last parts, and which will also have the maximum pull upon the collapsing toe portion to collapse it to the desired degree, or support it in full and extended position.

Referring to the details of the drawings: 15 1 is the toe part having an upper or tongue portion 2, separated from the main toe part by the slot or gap 3.

This tongue portion is provided with its slot in its under-face as at 4, for receiving 20 the upper end of the tongue link 5, which is mounted therein on the pin 6. The lower portion of the toe part is provided with a slot 7. In this slot is mounted an arched link 8 consisting of two parts. Each half 25 of this link is provided with end eyes 9 and bulged side portions 10, so that a space 11^a is provided between the body of the link portions, but their ends are brought closely adjacent to one another where they 30 bear upon and are supported by the spring pins 11 and 12, which are mounted respectively in the toe and heel parts of the last.

The heel part of the last is designated 13 and is provided with a slot 14, in which the 35 links operate. The spring pins 11 and 12 are preferably so mounted with the last that their ends are firmly supported by the last material, while the median portions of the pins are permitted to flex, because the 40 walls of the last are cut away as at 15. The last parts are joined together by a joint consisting of a concave portion 16 in the toe part and a convex portion 17 in the heel part. This convex portion extends something more than 180 degrees. A third pin 45 18 is located in this convex portion to one side of the center thereof and upon this pin is mounted the link 5, which is also located between the two parts of the link 8 in the 50 space 11^a, so that this link can freely operate without engagement with the link 8, but in cooperation therewith and in synchronism with the movements of the rest of the last.

It will thus be seen that as the parts are arranged the holes in the wood receiving the pins 11 and 12 are further apart than the holes in the ends of the metal link 8. This provides sufficient resistance to the passage 60 of dead center so that the parts are maintained in extended or collapsed position, as desired.

It will be understood that I do not desire to confine myself to mere details nor to specific materials, but comprehend within my 65

claims such modifications which may be necessary for the adaptation of the invention to varying conditions.

Having thus fully described my invention, what I claim as new and desire to 70 secure by Letters Patent, is:

1. In a last, a heel part and a collapsible toe portion having a tongue, said heel and toe parts being hinged to one another, means to pivotally join said heel and toe parts to 75 one another, and a link attached to said tongue portion and heel part to connect them to one another, whereby when the last is collapsed the toe portion will be collapsed also.

2. In a last, a toe portion, a heel portion, said toe portion being divided into a main part and a tongue part adapted to be moved away from one another, or drawn to one another, a hinge between the toe portion and heel portion, a link joining the heel portion and the main part of the toe portion, and a second link joining the tongue portion and the heel portion, whereby when the last is collapsed the tongue portion will 85 also be collapsed.

3. In a last, a heel portion, a toe portion, said toe portion consisting of a main part and a tongue part, a link joining said toe portion and heel portion, means for connecting said link to said respective portions, a second link joining the heel portion and the collapsing tongue part, and means for connecting said second link to the respective parts and a joint formed between said 95 toe and heel portions, whereby one will rock upon the other.

4. In a last, a heel portion, a toe portion, said toe portion consisting of a main part and a tongue part, a link joining said toe 100 portion and heel portion, means for connecting said link to said respective portions, a second link joining the heel portion and the collapsing tongue part, and means for connecting said second link to the respective parts and a joint formed between said toe and heel portions, whereby one will rock upon the other, said second link being mounted in said joint in the heel portion.

5. In a last, a heel portion, a toe portion, said toe portion consisting of a main part and a tongue part, a link joining said toe portion and heel portion, means for connecting said link to said respective portions, a second link joining the heel portion and the collapsing tongue part, and means for connecting said second link to the respective parts and a joint formed between said toe and heel portions, whereby one will rock upon the other, said second link being mounted in said joint in the heel portion, the point of mounting being off center of the joint.

6. In a last, a heel portion, a toe portion, said toe portion consisting of a main part 130

- and a tongue part, a link joining said toe portion and heel portion, means for connecting said link to said respective portions, a second link joining the heel portion and 5 the collapsing tongue part, and means for connecting said second link to the respective parts and a joint formed between said toe and heel portions, whereby one will rock upon the other, said second link being 10 mounted in said joint in the heel portion, the point of mounting being off center of the joint, said joint consisting of a projecting convex portion and a corresponding concave portion.
- 15 7. In a last, a heel part, a toe part, and a collapsing tongue portion of the toe part, a joint between the toe part and the heel part, a shoulder on said parts to limit the movement in one direction and portions cut 20 away from said parts to permit movement in the other direction, a link joining said parts, means for connecting said link to the respective parts, a second link joining the heel part to the collapsing tongue portion,
- 25 25 said parts and tongue portion being cut away to receive and permit of the movement of said links.
8. In a last, a heel portion, a toe portion, and a collapsing tongue portion, means connecting said toe portion and heel portion, means to permit of said portions to rock upon one another, means to connect the heel portion and the tongue portion, the point of connection of said 30 last mentioned means being located above a line joining the centers of the means connecting the toe and heel portions when the last is in extended position, but said point of connection of the tongue and heel portion being located below said line when the last is in collapsed position.
- 35 9. In a last, a heel portion, a toe portion, and a collapsing tongue portion, means connecting said toe portion and heel portion, means to permit of said portions to rock upon one another, means to connect the heel portion and the tongue portion, the point of connection of said last mentioned means to the heel portion being located above a line 40 joining the centers of the means connecting the toe and heel portions when the last is in extended position, but said point of connection being located below said line when the last is in collapsed position, said point of connection also being located off of the center, about which the last parts rock.
- 45 10. In a last, a heel part, a toe part, and a collapsing tongue portion, an arch-shaped link connecting said toe and heel parts, pins 50 mounted in said respective parts attaching the link thereto, a tongue link, a pin mounted in the tongue supporting said link, a pin mounted in the heel part supporting the other end of said link, and a joint between 55 said toe and heel parts to permit them to rock one on the other from collapsed to extended position and vice versa.
11. In a last, a heel part, a toe part, and a collapsing tongue portion, an arch-shaped link connecting said toe and heel parts, pins 70 mounted in said respective parts attaching the link thereto, a tongue link, a pin mounted in the tongue supporting said link, a pin mounted in the heel part supporting the other end of said link, and a joint between 75 said toe and heel parts to permit them to rock one on the other from collapsed to extended position and vice versa, said pin in the heel part for supporting the tongue link being located in the arch of the arched link.
12. In a last, a heel part, a toe part, and a collapsing tongue portion, an arch-shaped link connecting said toe and heel parts, pins 80 mounted in said respective parts attaching the link thereto, a tongue link, a pin mounted in the tongue supporting said link, a pin mounted in the heel part supporting the other end of said link, and a joint between 85 said toe and heel parts to permit them to rock one on the other from collapsed to extended position and vice versa, said pin in the heel part for supporting the tongue link being located in the arch of the arched link,
13. In a last, a heel part, a toe part, and a collapsing tongue portion, an arch-shaped link connecting said toe and heel parts, pins 90 mounted in said respective parts attaching the link thereto, a tongue link, a pin mounted in the tongue supporting said tongue link, a pin mounted in the heel part supporting the other end of said tongue link, and a joint between 95 said toe and heel parts to permit them to rock one on the other from collapsed to extended position and vice versa, said pin in the heel part for supporting the tongue link being located in the arch of the arched link,
14. In a last, a heel part, a toe part, and a tongue portion adapted to be moved relatively to the toe part, a two-part link connecting the toe and heel part, the ends of 100 said link being closely adjacent to one another and the sides separated from one another, a tongue link located between said sides, having one end connected to the tongue, and a joint between the toe part and the heel part to permit of the collapsing of the last, whereby when the last is collapsed the tongue portion will be drawn 105 down closely adjacent the toe part,
15. In a last, a heel part, a toe part, and a tongue portion adapted to be moved relatively to the toe part, a two-part link connecting the toe and heel part, the ends of 110 said link being closely adjacent to one another and the sides separated from one another, a tongue link located between said sides, having one end connected to the tongue, and a joint between the toe part and the heel part to permit of the collapsing of the last, whereby when the last is collapsed the tongue portion will be drawn 115 down closely adjacent the toe part,
16. In a last, a heel part, a toe part, and a tongue portion adapted to be moved relatively to the toe part, a two-part link connecting the toe and heel part, the ends of 120 said link being closely adjacent to one another and the sides separated from one another, a tongue link located between said sides, having one end connected to the tongue, and a joint between the toe part and the heel part to permit of the collapsing of the last, whereby when the last is collapsed the tongue portion will be drawn 125 down closely adjacent the toe part,
17. In a last, a heel part, a toe part, and a tongue portion adapted to be moved relatively to the toe part, a two-part link connecting the toe and heel part, the ends of 130 said link being closely adjacent to one another and the sides separated from one another, a tongue link located between said sides, having one end connected to the tongue, and a joint between the toe part and the heel part to permit of the collapsing of the last, whereby when the last is collapsed the tongue portion will be drawn down closely adjacent the toe part,

tongue link being so arranged that its point of connection with the heel part of the last, when the last is expanded, is above a line drawn through the centers of the points of connection of the first mentioned link parts and below that line when the last is in collapsed position.

15. In a last, a heel part having a cut-away face and a semicircular projection, a toe part 10 having a corresponding concave portion and a collapsing tongue portion, so that the parts may rock with respect to one another, a link connecting said toe and heel parts, pins connecting said link to the respective 15 parts, the distance between the centers of said pins in collapsed or fully extended position being less than the distance through the material of the last between such centers when the parts pass over dead center, 20 and a link connecting the tongue and heel portions to draw down the tongue portion when the last is collapsed, said link connecting the tongue to the heel being connected to the heel in the semicircular projecting 25 portion on the heel, off the center thereof.

16. In a last, a heel portion, a toe portion, a joint therebetween to permit the parts to rock on one another about a common axis, a collapsing tongue portion, a link connecting 30 the heel and toe portion, yielding pins in said heel and toe portions connecting the ends of the link to the heel and toe portions and so mounted in said heel and toe portions as to be permitted to flex when the parts 35 pass over dead center, and a tongue link connecting said tongue and heel portion.

17. In a last, a heel portion, a toe portion, a joint therebetween to permit the parts to rock on one another about a common axis, a 40 collapsing tongue portion, a link connecting the heel and toe portion, yielding pins in said heel and toe portions connecting the ends of the link to the heel and toe portions and so mounted in said heel and toe portion 45 as to be permitted to flex when the parts pass over dead center, and a tongue link connecting said toe and heel, the point of connection of the tongue link on the heel being above a line drawn between the centers of the spring pins, when the last is 50 collapsed.

18. In a last, a toe part, a heel portion, a collapsing tongue portion, a link connecting said toe and heel portions, a second link 55 connecting said tongue and heel portions, and spring pins supporting said first men-

tioned link, the ends of said spring pins being supported by the last parts which are cut away adjacent the central portions of said pins to permit of the flexing thereof, 60 the interior of said toe, heel and tongue portions being slotted to receive said links.

19. In a last, a heel part, a toe part, a collapsing tongue part, a semicircular projecting portion on said heel, and a corresponding concave portion on said toe to 65 form a rocking joint between the parts, a link connecting said parts, spring pins mounted in the respective parts to support said link, the last parts being cut away to 70 permit of the flexing of said links, and a tongue link connecting the heel and tongue to draw down the tongue when the parts are collapsed, the parts being so arranged that the excess of material of the last between the spring pin centers, when the last parts pass over dead center, will cause said pins to be flexed by the link when the parts pass from expanded to collapsed position and vice versa. 75

20. In a last, a heel part, a toe part, a collapsing tongue part, a semicircular projecting portion on said heel, and a corresponding concave portion on said toe to 80 form a rocking joint between the parts, a link connecting said parts, spring pins mounted in the respective parts to support said link, the last parts being cut away to 85 permit of the flexing of said links, a tongue link connecting the heel and tongue to draw down the tongue when the parts are collapsed, the parts being so arranged that the excess of material of the last between the spring pin centers, when the last parts pass over dead center, will cause said pins to be 90 flexed by the link when the parts pass from expanded to collapsed position and vice versa, the link connecting the toe and heel part consisting of two members having closely adjacent ends and separated side 95 walls, so that the tongue link can pass therebetween freely, said tongue link being connected to the heel on the joint portion, and so located on the projecting portion of the heel joint that while carried by the heel, it 100 is within the area of the toe and moves with respect to the toe so as to remove the tongue with respect to the toe. 105

In testimony whereof, I affix my signature.

GEORGE CLAUSING.
